Des. 239,077
Patented Mar. 9, 1976

239,077

SOLDERING IRON

Harold S. Foster, Huntington Beach, and Charles J. Ortega, Valencia, Calif., assignors to Eldon Industries, Inc., Hawthorne, Calif.

Filed Sept. 4, 1973, Ser. No. 393,926

Term of patent 14 years

Int. Cl. D8—05

U.S. Cl. D8—30

FIG. 1.

FIG. 2.

FIG. 3.

FIG. 4.

FIG. 5.

FIG. 1 is a side elevational view of a soldering iron embodying the new design of our invention;

FIG. 2 is a top plan view thereof;

FIG. 3 is a bottom plan view thereof;

FIG. 4 is a front elevational view thereof; and

FIG. 5 is a rear elevational view thereof.

The side of the soldering iron which is not illustrated is a mirror image of the side thereof which is illustrated.

We claim:

The ornamental design for a soldering iron, substantially as shown and described.
